UNITED STATES PATENT OFFICE.

LOUIS I. BECKWITH, OF BOSTON, MASSACHUSETTS.

LUGGAGE CARRIER.

Application filed June 25, 1921. Serial No. 480,376.

To all whom it may concern:

Be it known that I, LOUIS I. BECKWITH, citizen of the United States of America, and resident of Boston, Dorchester, in the county of Suffolk and State of Massachusetts, have invented new and useful Improvements in Luggage Carriers, of which the following is a specification.

This invention relates to luggage carriers 10 for automobiles and more particularly to an adjustable device of this character adapted to be detachably mounted upon the running board of the vehicle.

Devices of this type, to be acceptable to 15 the user, must be of a character such as to permit of their ready application to the running board without injury to the latter, and such that they may be removed at will and folded into compact form for transportation in the limited space available for such purposes in ordinary automobiles. It is also desirable that an appliance of this kind be 20 of variable length to accommodate the quantity of baggage to be carried, and if the 25 outer retaining wall thereof be made extensible for this purpose it is almost necessary that it be provided with members which may be extended transversely across the running board to form end walls for the luggage receiving compartment. For the compact folding of the device it then becomes 30 desirable to provide means whereby such end walls may be caused to lie in a plane substantially parallel to that of the outer retaining 35 wall when the parts are collapsed for storage. Devices of this kind should be of relatively light construction in order to permit 40 ready handling of the same, as well as to avoid incumbering the vehicle with useless weight, but at the same time should be 45 strong and capable of firm and secure connection to the running board. For the purpose of properly securing the device to the running board, strong supporting posts should be provided at intervals, to which 50 posts the clamping means may be secured. Moreover the clamping means employed should be of relatively heavy construction in order to secure a firm grip upon the edge 55 of the running board. When, as in some cases, the extensible wall portion of the device is of lazy-tongs construction, proper connections must be provided between such wall and the supporting posts therefor, whereby to permit the expansion and con-

traction of the elements forming the wall, while at the same time the supporting of such lazy-tongs device at points adjacent its upper and lower edges is very desirable in order to secure the requisite strength and 60 rigidity.

When the wall is constructed in the manner just indicated, it is necessary to provide joints between the intersecting bars of which the wall is composed, and as such bars 65 are commonly painted or enameled, it is desirable to provide joints of a character such as to permit of the relative movement of the bars without danger of marring or removing portions of the enamel or paint 70 adjacent the pivot point.

The present invention has for its object the provision of a device embodying the various desirable features above pointed out, and in a simple and inexpensive form which 75 may be applied to automobiles of all usual makes without substantial change therein or injury thereto.

A preferred embodiment of means for carrying the invention into effect is disclosed in the accompanying drawings in which,—

Figure 1 is a side elevation of an automobile having the device of the invention applied thereto;

85

Figure 2 is a rear view of the luggage carrier of Fig. 1 showing the same in collapsed condition;

Figure 3 is a fragmentary front elevation of the right-hand end of the device as shown 90 in Fig. 1;

Figure 4 is a fragmentary plan view illustrating the device shown in Fig. 3;

Figure 5 is a vertical transverse section through the central supporting post of the 95 device shown in Fig. 1;

Figure 6 is a front elevation, illustrating a slight modification of the device shown in Fig. 1 but to somewhat larger scale;

Figure 7 is a fragmentary front elevation 100 of the upper end of the left-hand post of the device shown in Fig. 1;

Figure 8 is a plan view of the device shown in Fig. 7;

Figure 9 is a plan view of the device 105 detached from the automobile, and in extended condition;

Figure 10 is a fragmentary front elevation of the upper end of the central supporting post, to larger scale;

110

Figure 11 is a cross sectional view illustrating one mode of connecting intersecting bars of the expandible wall device; and

Fig. 12 is a transverse cross section illustrating a modified and preferred form of joint for connecting relatively movable members of the device.

Referring to Figs. 1 to 5, an automobile of any usual construction is indicated grammatically at 1, such automobile being provided with the running board 2 and with the fenders 3, 4, respectively. Mounted upon the running board 2 is the device forming the subject-matter of the present invention, this device comprising the end posts 5, 6, the center post 7 and the expandible side retaining wall 8. The supporting posts are preferably formed of relatively thin but rigid material having their lower 20 extremities bent at substantially right angles to form the angularly disposed portions 9 (Fig. 2).

On the lower end of each of the posts is secured a clamp whereby such post may be secured to the running board. The clamps for the end posts 5 and 6 are of duplicate construction and each preferably comprises an integral bar bent into substantially J form whereby to provide a short horizontal 30 arm 10, the long horizontal arm 11 and the vertical connecting member 12. The member 10 rests upon the upper surface of the member 9 of the post, and may be connected thereto by means of a rivet 13 or in other 35 suitable manner. The member 12 of the clamp is positioned in contact with lower portion of the main body of the post and is secured thereto by means of a rivet 14 or bolt. The clamp member is preferably of 40 heavier material than that of which the post is formed and may, if desired, be of hardened steel whereby the clamp is enabled to withstand the clamping pressure in a reliable and satisfactory manner.

Aligned openings are formed in the member 9 and the member 10 of the clamp, such openings being internally screw-threaded for the reception of a clamping screw 15. This clamping screw may be provided with 50 an angularly disposed head 16 whereby it may be turned or, if desired, a hand wheel, nut or other equivalent means may be substituted, whereby to permit of the turning of the screw either by hand or by the use of 55 a suitable wrench.

The upper or clamping end of the screw is preferably provided with a swivel contact member 17, such member serving for engagement with the under side of the running board and permitting the tightening of the screw without substantial injury to the running board. For retaining the screw 15 in adjusted position, such screw may be provided with a lock nut 18 of usual construction.

The clamping device for the central post 7 is of somewhat different construction from that of the end posts, such clamping member consisting of a substantial U shaped frame having the horizontal members 19, 20, respectively, connected by the vertical member 21. The member 20 is secured to the member 9 of the post 7 by means of a rivet 22 while the member 21 is connected to the lower part of the post 7 by the rivet 23. The upper member 19 of the clamp has riveted thereto at the point 24 a plate 25 which is provided with a tang 26 passing through an opening in the post 7 and riveted over on the outer side thereof at 27. As indicated in Fig. 2, the members 19, 20 of the central clamp are placed somewhat further apart than are the members 10, 11 of the end clamps for a purpose to be hereinafter described.

The long arms 11 of the end clamp members serve as the bottom elements of wings forming end walls for the device, the posts 5, 6 serving respectively as one side member of such wings. Such wings or end walls 90 each further comprise an angularly bent bar having the horizontal member 28 and the vertical member 29, such members being riveted at points 30, 31, respectively, to an end post and to the corresponding clamp member 11, these constituting a substantially rectangular frame. Each end wall may also comprise the intermediate vertical member 32 riveted at its upper and lower ends to the members 28 and 11, respectively. It will thus be clear that the end walls are rigidly connected to the end posts and to the end clamping members and extend in directions substantially perpendicular to the plane of the end posts.

The retaining wall is preferably of lazy-tongs construction, comprising pairs of intersecting bars such as 33, 34, such bars being pivoted together at their points of intersection as indicated at 35. The opposite ends of the bars constituting the several pairs are also pivoted, at points such as 36, 37, to the ends of the bars of adjacent pairs, thus forming a lazy-tongs of usual and well-known construction. At each end of the lazy-tongs device the end members thereof are connected to the respective supporting posts and for permitting the relative movement of such end members the following connecting devices are provided:

Referring to Figs. 3 and 4, the connecting device employed is indicated as comprising a short lever arm 38 pivoted as at 39 to the post and provided adjacent its free end with a slot 40. Looped through the slot 40 is the central portion of a strap member 41, the ends of said strap indicated at 42, 43, respectively, being bent into substantial parallelism and including between them the end portion of one of the

bars, as 33. Passing through aligned openings in the end of such bar and in the members 42, 43, is a pin or rivet 44 which serves to connect said members together whereby to permit relative movement of the bar and strap. With this arrangement it is evident that the end of the bar 33 may move freely in a vertical plane, while at the same time the lever 38 with the post to which it is connected may swing horizontally relative to the strap by reason of the loose connection of the latter at the slot 40. While the above connecting means has been described as applied to the end of the bar 33, a similar device is employed for connecting the end of the bar 34, such connecting means being disposed at the upper and lower parts of the supporting post respectively.

Other means suitable for connecting the extensible wall 8 to the supporting post are shown in Figs. 7 and 8.

In this arrangement the post 5 is shown as being provided with a short lever arm 45 pivoted thereto by means of the pivot pin 46. This lever 45 constitutes one leaf or flap of a hinge of ordinary form, the other flap thereof being indicated at 47, these flaps being connected together by the pintle pin 48. To the outer end of the flap member 47 is secured the upper end of one of the bars such as 34^a of the extensible wall, this bar being connected by means of a pivot pin 50 to the flap member. A similar hinge connection may be employed adjacent the bottom end of the post as indicated in Fig. 1.

While either of the connecting members just described may be used in securing the extensible wall to the posts, and while all of such forms may be used in the same structure if desired, that indicated at the right-hand side of Fig. 1 and in detail in Figs. 3 and 4 is preferred, this form being simple and cheap to construct and giving very efficient results in service.

The extensible wall may be connected to the central post 7 as by means of a pivot pin 55 which also serves as the connecting element for a pair of the intersecting bars such as 33^a, 34^a of which the wall is composed. With this arrangement, however, it is necessary to provide for the vertical movement of the point of connection of the bars 33^a, 34^a, respectively, which are connected to the bars 34^m, 33^m at the points 60 61, respectively. For this purpose, the upper end of the central post 7 is provided with a longitudinal slot 62, and the pivot pin 63 which serves to connect the bars 33^a, 34^a is elongated and passes through the slot 62, this pin thus serving not only to connect said bars, but also to guide their upper ends for vertical movement.

The several intersecting bars forming the extensible wall of the device are pref-

erable of relatively thin material, and at their points of intersection may be secured together if desired as indicated in Fig. 11, wherein two such bars as 33, 34, are shown as having interposed therebetween one or more washers such as 64, 65, the bars being pivotally connected by means of a rivet or bolt 35^a. In accordance with a preferred form of arrangement, however, each of the bars as 33^a, 34^a, respectively (Fig. 12) is provided with an outstanding boss such as 67, 68, such bosses being directed toward each other and provided with engaging surfaces 69, 70, respectively. Aligned openings are formed through such bosses for the reception of a pivot pin or rivet 35^a. While these bosses may be formed in any desired manner, it is preferred to form them by striking up the metal from the opposite side of the bar, thus forming depressions in the opposite sides of the bars in which the heads of the connecting rivet or bolt may be seated.

In accordance with the modification illustrated in Fig. 6, the connections between each of the posts 5, 6, and the respective ends of the extensible wall member are of the same type, being such as is shown in detail in Figs. 3 and 4, the arrangement in other respects being like that of Fig. 1. With either of the arrangements described, the extensible wall member permits of the expansion of the device to a length substantially equal to the length of the running board or of its collapse into very small dimensions, the lazy-tongs structure being rigidly supported in all positions of adjustment by the connection of its upper and lower edges to the several posts. When the lazy-tongs structure is to be collapsed, the end wall frames, comprising the members 28 and 11, which during the use of the device stand substantially at right angles to the plane of the extensible wall, may be swung rearwardly to lie in planes substantially parallel to that of the wall, such swinging being permitted by reason of the universal joint connections between the posts and the ends of the extensible member. When the end frames are swung into parallelism with the extensible member, the members 11 of such frames pass between the opposed members 19, 20 of the clamp carried by the central post, and when so positioned may be retained therein by tightening the clamping screw forming a part of said clamping device. In this condition, the structure may readily be transported without any danger of its accidental expansion or of the swinging outwardly of the end frame members.

By the employment of connecting joints such as indicated in Fig. 12, it is unnecessary to interpose washers between the connected elements, and as the connected parts

are spaced from each other by their integral bosses; there is no danger of their rubbing together adjacent the joint with consequent breaking of the enamel or paint with which they may be coated and the consequent rusting of the metal.

Having thus described the invention in a preferred embodiment of the same together with the mode of use thereof, what I claim and desire to secure by Letters Patent of the United States is:

1. A device of the class described comprising a retaining wall of lazy-tongs construction comprising a pair of pivotally connected bars, a post for supporting said wall, means comprising a plurality of pivotally connected elements intermediate the bars and post for securing an end of one bar to the upper part of the post, and securing means for pivotally connecting an end of the other bar to the lower part of the post, said securing means being constructed and arranged to permit relative movement of the ends of said bars in a direction longitudinal of the post.

2. In a device of the class described, a supporting post, a retaining wall comprising relatively movable members, and a connecting device for securing one of said members to the post, said connecting device comprising a lever arm pivoted to the post and swingable in a vertical plane, said arm having an open adjacent its free end, a strap having its central portion looped through said opening, the end portions of said strap engaging opposite sides of said movable member, and a pivot pin passing through and connecting the ends of the strap and said member.

3. A luggage carrier comprising a pair of relatively thin metal bars arranged in parallel planes, each of said bars having a

boss struck up from its surface and extending toward the plane of the other bar, and a pivot pin passing through aligned axial openings in the respective bosses and constituting a pivotal connection for said bars.

4. A luggage carrier having a retaining wall of lazy-tongs construction, said wall comprising a plurality of pairs of intersecting metallic bars, the bars of each pair having bosses projecting from their adjacent faces at their point of intersection, and means for pivotally connecting said bars at such point, and with their respective bosses in engagement one with the other.

5. A luggage carrier including a retaining wall of lazy-tongs construction having terminal pivotally connected bars, an end post for the carrier, and means connecting the bars with the end posts, said connecting means including members pivoted to the post for swinging movement longitudinally thereof and additional members hinged to the first members to swing substantially at right angles thereto and means pivotally connecting the latter members with the bars of the retaining wall.

6. A device of the class described including a retaining wall of lazy-tong construction having terminal intermediately pivoted bar portions, a supporting end post for the wall, and hinge members intermediate the wall and the posts, said hinge members having parallel pivot connections securing their respective leaves to the post and to the wall, said connections lying in a plane at right angles to the pintle portion of the hinge.

Signed by me at Boston, Massachusetts, this 16th day of May, 1921.

LOUIS I. BECKWITH.
